JOINT STRUCTURE BETWEEN UNDER-
FRAME AND SIDE WALL SUBASSEM-
BLIES OF RAILWAY CARSAlbert G. Dean, Narberth, Pa., assignor to The
Budd Company, Philadelphia, Pa., a corpora-
tion of PennsylvaniaContinuation of application Serial No. 508,873,
November 4, 1943. This application September
27, 1945, Serial No. 618,961

13 Claims. (Cl. 105—397)

1

The invention relates to vehicle bodies and particularly to such bodies adapted for use in railway cars.

This application is a continuation of applicant's original application, Serial No. 508,873, Vehicle body construction, filed November 4, 1943, now abandoned.

It is an object of the invention to facilitate the assembly of such bodies, and this object is in large part attained by first assembling the upright or side walls and the underframe as separate subassemblies, and by providing these subassemblies with novel final assembly joint structures which facilitate their joinder together in final assembly in such manner as to provide an unusually strong side sill construction in the region of the joinder.

Other and further objects and advantages and the manner in which they are attained will become apparent from the following detailed description when read in connection with the drawings illustrating one embodiment of the invention and forming a part of this specification:

In the drawings,

Figure 1 is a diagrammatic plan view of a railway car underframe subassembly;

Figure 2 is a side elevational view of the framework of a side wall subassembly mating the underframe of Figure 1;

Figure 3 is a fragmentary detail vertical transverse sectional view on a larger scale of the final assembly joint structure between the underframe and side wall subassemblies shown in Figures 1 and 2;

Figure 4 is an exploded sectional view, similar to Figure 3, showing the subassemblies entering into the final assembly joint structure;

Figure 5 is a fragmentary perspective view, as seen from the inside of the joint structure, with the outer paneling left off; and

Figures 6 and 7 are detail horizontal sectional views taken, respectively, substantially along the lines 6—6 of Figure 3 and 7—7 of Figure 4.

In the illustrated embodiment of the invention, the underframe comprises, as shown in Figure 1, a center sill 10 with transversely widened end extensions 11, and suitably longitudinally spaced transverse members, as the spaced floor beams 12 and bolsters 13, connected to the center sill and its end extensions.

A typical floor beam 12 is shown in the detail views, Figures 3 to 7, as comprising a generally Z-section member, having a deep vertical web portion and having the margins of its arms vertically flanged toward the central horizontal plane of the web portion. Of course, the par-

2

ticular form of the transverse members may be varied from the preferred form shown without departing from the main features of the invention.

According to the invention, the transverse members 12 of the underframe are interconnected at their opposite ends by longitudinally extending through-running side sill members 14 of generally angular form, including a horizontal arm 15 overlying the tops of the transverse members 12, 13 and secured thereto, as by spot welding, and a vertical arm 16 overlapping the end faces of the transverse members and secured thereto in a manner to be described hereinafter.

The horizontal arm 15 is formed with a shallow marginal, outwardly presenting channel 17 to the top wall of which is secured, as by welding, the margin of the transversely corrugated floor sheet 18. The flooring is additionally secured to the transverse members 12 and is supported by spaced longitudinally extending stringers 19.

To form a strong final assembly joint structure and to give additional column strength to the side sill member 14, its vertical arm is formed in its lower margin with a vertically, preferably upwardly facing shallow channel 20.

All the parts so far described may be assembled into the underframe subassembly, and it may then be turned upside down and the usual accessories assembled therewith without the inconvenience of assembling such accessories with the underframe from the bottom. Among the usual accessories are, as commonly known: draft gear yoke, the coupler, centering device for the coupler, the coupler carrier, all major piping and conduits, battery boxes, tanks and casings, electric generating unit and the air conditioning installation.

When the underframe is so inverted, either before or after the application of the accessories, downwardly extending skirt supports 21 may be secured in place. These are usually secured one in the region of each transverse member, as the floor beams 12.

The supports 21 may be sheet metal brackets wide at the top and tapering to the bottom, their top and outer margins being laterally flanged, and the outer margin being curved to the contour of the skirt. The top marginal flange 22 overlaps the end of the adjacent floor beam 12 and the bottom of the channel 20 of side member 14 and is secured thereto in the overlap, as by spot welding, see Figure 7.

The support 21 is further stiffened and the end

of the floor beam 12 is secured to the vertical arm 16 of the sill member 14 by an angle 23 having one arm overlapping the body or web of support 21 and the web of floor beam 12 and secured thereto in the overlap, and its other arm overlapping the vertical arm 16 of the sill member 14 and likewise secured thereto in the overlap, as by spot welding, see Figures 3 to 7.

With the underframe so subassembled, as shown in Figure 1 and the exploded view of Figure 4, it is in condition for final assembly with the side wall subassembly.

The side wall subassembly may comprise the separate framing assembly shown in Figure 2 including the spaced vertical posts 24, the top rail 25, the intermediate rail 26 below the window openings and the novel bottom side sill member 27 forming a principal part of a bottom rail interconnecting the posts 24 some distance above their lower ends. The posts 24 may be termed transverse members interconnecting the longitudinal rails. Diagonals 28 interconnect the rails and posts through gussets, as 29.

Except for the bottom construction adapting the side wall framing subassembly for easy final assembly with the underframe subassembly and for providing therewith a strong final assembly joint structure, the rest of the side frame may be of any suitable known construction.

The side sill member 27 is a through-running member of somewhat heavier gauge than the other members of the side wall framing and corresponding generally in gauge to that of the side sill member 14 of the underframe subassembly. It comprises a vertically deep body portion 30 which may be stiffened by a rib 31, this portion overlapping the inside of the posts 24, and secured thereto in the overlap as by spot welding, see Figures 2 to 5. The posts 24 are shown to be of flanged channel section, but may be of other form as desired.

Along the lower margin of body portion 30, sill member 27 is extended generally horizontally away from the posts by a portion 32 which is formed in its margin with an outwardly presenting channel 33, the bottom side wall of this channel forming a final assembly joint structure and being provided with a short edge flange 34 for added stiffness.

As will be obvious from the drawings, the side sill member 27 takes the place of the gussets at the inner sides of the posts and diagonals and may also serve as the outer wall of a heater duct in the final assembly.

The side wall subassembly so far described and shown in separated relation from the underframe subassembly in Figures 2 and 4, may be brought to the final assembly relation therewith shown in Figures 3 and 5. In this position the bottom side wall of the outwardly facing marginal channel 33 of the side sill member 27 comes into overlapping engagement with the horizontal arm 15 of the side sill member 14 on the underframe subassembly and can be readily secured thereto by a line of spot welds. At the same time, the lower ends of the posts 24 telescope into the shallow upwardly facing channel 20 and their inner faces overlap the vertical arm 16 of the underframe sill member 14 and are readily secured thereto in the overlap by spot welding, Figures 3 and 6. Thus the lower ends of the posts are securely anchored against lateral deflection and form with the side sill members 14 and 27 of the underframe and side frame subassemblies, respectively, a substantially box-section side sill having high col-

umnar strength. With this arrangement, the final assembly is effected with a minimum of welding, and since all the final assembly joint parts are open and accessible, the welding in final assembly is facilitated. Also, with this arrangement, there is no necessity of lining up the transverse members of the underframe and side wall subassemblies.

The through-running longitudinally corrugated skirt sheet 35 may be subassembled into a unit, as shown in Figure 4, with a flanged channel 36 forming a rub rail and an angular section bottom rail 37, and this unit may now be brought into the position shown in Figure 3 and welded to the outer faces of the posts 24 and the skirt supports 21. This subassembly, when secured in place, adds further to the strength of the joint between the underframe and side subassemblies.

The outer sheathing, as 38, is finally applied to the side frame in the regions above the bottom rail as defined by the outside flanged channel 36.

While the invention has been herein described in detail as embodied in a specific construction, it will be understood that changes and modifications may be made by those skilled in the art without departing from the main features of the invention, and such changes and modifications are intended to be covered in the appended claims.

30 What is claimed is:

1. A vehicle body construction comprising a side wall subassembly including vertical posts and a through-running side sill member interconnecting the posts some distance above their lower ends, said side sill member having its lower marginal portion spaced from the posts and formed as an outwardly presenting channel, and an underframe subassembly including transverse floor beams interconnected at their ends by a generally downwardly and inwardly facing angular section through-running side sill member overlapping through the horizontal and vertical arms of its angular section the tops and ends of said floor beams, respectively, and secured thereto, the lower margin of said vertical arm being formed with an upwardly facing channel, the side wall subassembly, in final assembly, having the bottom side wall of the marginal channel of its side sill member overlapping and secured to the horizontal arm of the underframe sill member and its posts overlapping and secured to the vertical arm of said underframe sill member with their bottom ends telescoped into the upwardly facing marginal channel thereof.

55 2. A joint structure between vehicle body underframe and side wall subassemblies comprising a through-running side sill member on said underframe subassembly having horizontal and vertical faces, the latter terminating in an upwardly facing shallow channel, and a through-running side sill member on said side wall subassembly and vertical posts interconnected by said side sill member in subassembly, said through-running side sill member on the side wall subassembly overlapping and being secured to the horizontal face of said underframe side sill member and the posts telescoping into the upwardly facing channel and overlapping and being secured to the vertical face of said underframe side sill member.

60 3. A joint structure between vehicle body underframe and side wall subassemblies, comprising a through-running side sill member for and subassembled with each said subassembly, the sill member on the underframe subassembly inter-

connecting transverse members of the underframe, the sill member on the side wall subassembly interconnecting side wall posts with their lower ends projecting therebelow, and the sill member and posts of the side subassembly overlapping and forming final assembly joints with parts of the underframe side sill member and being secured thereto in final assembly.

4. A joint structure according to claim 3, in which the underframe side sill member, the side wall side sill member and the posts are so arranged as to form in the final assembly a substantially box-section side sill.

5. A joint structure between vehicle body underframe and side wall subassemblies, each said subassembly comprising longitudinally spaced transverse members and a through-running side sill member interconnecting the transverse members, the side sill members, in final assembly, having overlapping parts accessible for joinder throughout the overlap and secured together in the overlap, the ends of the transverse members of the side wall subassemblies overlapping in final assembly another part of said underframe sill member and secured thereto in final assembly.

6. A joint structure between vehicle body underframe and side wall subassemblies, each said subassembly comprising longitudinally spaced transverse members and a through-running longitudinal side sill member of angular cross-section, the side sill member of the side wall subassembly having a marginal flange overlapping a horizontally extending arm of the side sill member of the underframe and the lower ends of the transverse members of the side wall subassembly telescoping an upwardly facing marginal portion of the underframe side sill and overlapping a vertical arm thereof, the parts being secured together in the overlaps in final assembly.

7. A joint structure between the underframe and a side wall of a railway car comprising a through-running generally angle-section underframe side sill member connecting transverse members of the underframe, said angle-section sill member having a horizontal portion and a vertical portion, a through-running side sill member connecting in subassembly posts of the side wall with the ends of the posts projecting therebelow, said side sill member on the side wall having an edge flange overlapping the horizontal portion of said underframe side sill member and being secured thereto in the overlap, the ends of the posts projecting below the side wall side sill member, overlapping the vertical portion of the underframe side sill member and being secured thereto in the overlap.

8. An underframe subassembly for vehicle bodies comprising longitudinally spaced transverse members and a through-running side sill member of generally angle-section overlapping the tops and ends of said transverse members and secured thereto in the overlap, at least certain of said transverse members having connected with them and to the respective adjacent portions of the side sill member, a skirt support extending downwardly beyond the side sill member.

9. An underframe subassembly for vehicle bodies comprising longitudinally spaced transverse members and a through-running side sill member of generally angular cross-section having a horizontal arm overlapping the tops of the transverse members and secured thereto in the overlap and having further a vertical arm flank-

ing the ends of the transverse members and secured thereto through angle members each having one arm overlapping and secured to the end of an associated transverse member and another arm overlapping and secured to the vertical arm of said sill member.

10. An underframe subassembly for vehicle bodies comprising longitudinally spaced transverse members, and a through-running side sill member of generally angular cross-section having a horizontal arm overlapping and secured to the tops of said transverse members and a vertical arm flanking the ends of the transverse members and flanged in its lower margin substantially in the plane of the bottoms of said transverse members, and a skirt support associated with at least certain of said transverse members and interconnecting the vertical arm and its lateral flange on the side sill member with the adjacent transverse member.

11. A joint structure between vehicle body underframe and side wall subassemblies comprising through-running side sill members subassembled with each of said subassemblies and skirt supports subassembled with said underframe subassembly, the sill member on the underframe subassembly together with said skirt supports interconnecting transverse members of the underframe, the sill member on the side wall subassembly interconnecting side wall posts with their lower ends projecting therebelow, the sill member and posts of the side subassembly overlapping and forming final assembly joints with parts of the underframe side sill and being secured thereto in final assembly, and a skirt subassembly, comprising sheathing and top and bottom stiffeners secured to the margins of the sheathing, secured in final assembly to the lower ends of the posts and to the skirt supports.

12. A joint structure between an underframe subassembly and an upright wall subassembly of a vehicle, comprising a marginal sill on said underframe subassembly overlapping by a generally horizontal arm the top and by a generally vertical arm the ends of adjoining underframe members, a marginal sill on said upright wall subassembly overlapping by an upright arm upright marginal portions of adjoining members of said wall subassembly and having along the lower margin of said upright arm a generally horizontal arm which overlaps and is secured to the horizontal arm of the underframe sill so as to constitute a final assembly joint between the two subassemblies.

13. A joint structure according to claim 12, comprising portions on said upright wall subassembly which extend downwardly beyond said horizontal arms and are overlappingly connected in final assembly with the vertical arm of the underframe sill.
